Geo. P. Kimmel

UNITED STATES PATENT OFFICE.

JOHN G. REED, OF LOS ANGELES, CALIFORNIA.

TOY.

Application filed October 28, 1921. Serial No. 511,088.

To all whom it may concern:

Be it known that I, JOHN G. REED, a citizen of the United States, residing at Los Angeles, in the county of Los Angeles and State of California, have invented certain new and useful Improvements in Toys, of which the following is a specification.

This invention relates to toys and more particularly to spinners of the projectable type.

The object of the invention is to provide a toy of this character including members separably connected and so constructed that the rotation of one will operate to release and project the other, the impetus imparted to the projected member being sufficient to carry it into the air a considerable distance.

Another object is to provide a device of this character including two separably connected rotary members, the rotation of one being operable to release and project the other, said device being equipped with means for controlling the holding power or resistance set up by the speed of the rotary actuating member as against the resistance of the projectable member in separating the latter from the former.

Another object is to so construct the projectile that it will be retained in upright position during its flight and on its descent at a given drop will have a tendency to reverse thereby causing the drop to be easily made.

Another object is to provide a toy composed of separably connected members one of which is rotatable to project the other, the projectable member being in the form of a rod equipped with a propeller at one end and at its other end with an angular socket engaging terminal to be engaged with the rotary member, the length of this angular rod end and its insertion within the socket of the rotary member controls the holding power of resistance set up by the speed of the rotary member and against the resistance of the propeller in lifting the projectile out of the socket. It is of course understood that if this squared or angular end of the rod was one inch long it would take more power to lift it out of the socket than if it were one-half or a quarter of an inch long, since the propeller would have to lift just that much more to overcome the hanging or the resistance of the angular end in the socket.

With these and other objects in view, the invention consists in certain novel features

of construction as hereinafter shown, described and claimed.

In the accompanying drawings:

Figure 1 represents a side elevation of a toy constructed in accordance with this invention, parts being broken out and in section.

Figure 2 is a transverse section taken on the line 2—2 of Fig. 1, and,

Figure 3 is a similar view taken on the line 3—3 of Fig. 1.

In the embodiment illustrated the toy constituting this invention comprises a handle member 1 and a projectable member 10 separably connected in a manner and for a purpose presently to be described. The handle member 1 comprises a hand grip 2 of wood or any suitable material having a bore extending longitudinally therethrough in which is mounted to rotate a shaft 3 which extends beyond one end of the hand grip 2 and is equipped with disk-like heads or plates 4 and 5 spaced a sufficient distance to form a cord receiving spool 6. The plate 4 is formed adjacent one end of the hand grip 2, while the shaft 3 at the other end of the hand grip is upset to prevent its withdrawal from the grip.

Mounted on the outer face of the plate 5 is an inverted U-shaped bracket member 7, the cross bar 8 of which is apertured for the passage of the projectile rod as will be presently more fully described. The plate 5 and the adjacent end of the rod or shaft 3 has an angular socket 9 formed therein which registers with the aperture in the cross bar 8 of the member 7 and which may be of any desired depth.

The plate 4 which forms one flange or head of the spool 6 has a tangentially formed slot 4^a therein through which is designed to be inserted the knotted end 19 of an actuating or spinning cord 18. This cord 18 is of a suitable length to be wound tightly and closely around the spool 6 throughout its entire length and leave a sufficient hand hold for a pull to be exerted thereon. The outer end of the cord 18 is preferably provided with a stop or grip member 20 to prevent the hand of the operator from slipping when pulling on the cord.

The projectile or propeller member 10 comprises a rod 11 having an angular terminal 11^a at one end which is adapted to be inserted through the aperture in the cross bar 8 of the bracket member 7 and to enter

the socket 9 in the member 1. The upper end of the rod 11 is threaded as shown at 12 and has detachably mounted thereon a propeller 13 composed of diametrically opposite longitudinally aligned twisted blades 13^a, two of which are here shown although obviously any desired number may be employed. This propeller 13 has an aperture midway its ends for the passage there-through of the rod 11 and is secured on the rod by nuts 14 and 15 arranged on opposite faces thereof and threaded on said rod with washers 16 and 17 arranged between the nuts and the adjacent faces of the blade or propeller 13. After the blade or propeller 13 is applied, the outer nut 14 is preferably upset or otherwise locked to prevent its being thrown off during the revolution of the propeller.

20 In the use of this toy, the blade or propeller 13 having been secured to one end of the rod 13 as above described, and the cord 18 having been wound on the spool 6 in the manner above set forth and as shown in Fig. 1, the rod 11 is then inserted through the cross bar 8 and the terminal 11^a thereof entered in the socket 9 of the member 1 and the device is ready for use. The hand grip 2 is then grasped by the left hand of the operator with the toy held in upright position and the cord 18 is grasped by the right hand and a fast hard pull imparted thereto, the faster the better. This rapid unwinding of the cord from the spool 6 operates to rapidly rotate the spool and the member 10 connected therewith and when a predetermined speed is reached the propeller will lift from out the socket 9 and ascend into the air. The height to which the member 10 will be projected depends entirely upon the pull given the cord and the length of the angular member 11^a. The rod 11 and the propeller 13 are so proportioned that the rod will balance the propeller and operate to retain it in upright position during its flight. When constructed as above set forth, the propeller at a given drop has a tendency to reverse and thereby cause the drop to be made easily since the reverse motion of the propeller checks the fall to a certain extent and if no wind is blowing, the projectile 10 will rise and fall almost vertically.

As has been hereinbefore mentioned, the length of the angular terminal of the rod 11 controls the holding power or resistance set up by the speed of the spool 6 and against the resistance of the propeller 13 in lifting

out of the socket, for instance, the longer this terminal is the greater resistance will be necessary to lift the propeller and consequently the more rapidly the spool will have to be rotated, and obviously, the shorter the end, the less resistance. On the other hand, it must be left a sufficient length so that the propeller will not lift the rod out of the socket until sufficient speed is attained to lift the propeller to a given height, say from seventy-five to a hundred feet more or less. With the device constructed as shown in the drawing, a proper pull exerted on the cord will carry the propeller up almost out of sight.

The preferred embodiment of the invention is disclosed in the drawings and set forth in the specification but it will be understood that any modifications within the scope of the claimed invention may be made in the construction without departing from the principle of the invention or sacrificing any of its advantages.

What I claim is:—

1. An aerial toy comprising two oppositely directed propeller blades, an elongated stem central thereto, said stem being central to the blades and centrally carrying them and terminating remote from the blades in a non-circular end, a handle, a spool rotatable on the handle, an elongated bracket member constituting an axial bearing for the stem mounted on the spool, and the spool and stem having coacting non-circular connecting means for causing a rotation of the propeller and spool until the rotational speed of the propeller overcomes the frictional engagement of the propeller stem with the spool.

2. An aerial toy comprising balanced oppositely acting propeller blades, an elongated carrying stem central and at right angles thereto, and terminating remotely from the blades in a non-circular end, a handle, a spool rotatable on the handle, an elongated bracket member constituting an axial bearing for the stem and mounted on the spool, said spool having coacting parts for rotating the propeller and spool until the rotational speed of the propeller overcomes the frictional engagement of said propeller stem with the spool, and the stem and blades are rotated to cause the reversal of relation of the blades and stem on the return thereof toward the ground.

In testimony whereof, I affix my signature hereto.

JOHN G. REED.
